PROCESS OF CARRYING OUT CHEMICAL REACTIONS WITH LIQUIDS.

Application filed September 4, 1920. Serial No. 403,288.

Our invention relates to a process for carrying out chemical reactions of various kinds, but relates especially to a process for carrying out reactions whereby hydrocarbons of a comparatively low boiling point may be derived from hydrocarbon liquids having a higher boiling point.

The object of our invention is to provide a process by means of which chemical reactions of various kinds may be carried out in an advantageous manner, but the object of our invention is especially to provide a process whereby solvents or fuels of a comparatively low boiling point may be derived from hydrocarbon liquids having a higher boiling point. In general, our invention relates to a process of subjecting organic liquids of various kinds, such as alcohols, ketones, ethers, esters, aldehydes, amines, acids, anhydrides, halogen derivatives, phenols, and nitro-compounds to dissociation or decomposition, so as to form various products, but it relates more particularly to the dissociation or decomposition of hydrocarbons, particularly hydrocarbons obtained from or contained in petroleum oils, coal tar oils, distillates, or those derived from shales. The object of our invention is, furthermore, to provide a process by means of which the influences of surfaces of liquids may be utilized to the fullest extent, so as to bring about reactions in one or more of several liquids, the surfaces of which are adjacent to one another. While the theory upon which the process operates to bring about the reactions in question due to the presence of said surfaces is not known to the fullest extent, we do know that these reactions are brought about by reason of the presence of the surfaces of the respective liquids in positions adjacent to one another, and it would seem, furthermore, that at least two of the active causes in starting these reactions are the surface energy which acts as a stress in displacing the chemical equilibria of a liquid system, and the chemical or structural orientation of the molecules of substances in liquid form, which is known to exist in the surfaces of the liquids. Furthermore, in our process changes in temperature and concentration of the reacting molecules are utilized in the furtherance of the reactions, as these two stresses are also active in displacing the chemical equilibria of the liquid system. Changes in pressure

have very little effect in carrying out our process, so far as causing the reactions is concerned, inasmuch as changes in pressure have little or no effect upon liquids, which are only slightly compressible. In accordance with the law relating to liquid systems to the effect that, when a stress is brought to bear upon a system in equilibrium by which the equilibrium is displaced, the equilibrium is displaced in that direction which tends to undo the effect of the stress, our process is designed to bring about the production of compounds having a smaller surface tension from compounds having a greater surface tension, by the application of a stress affecting the surface energy of the liquids present in the liquid system. Surface energy comprises two factors, surface tension and extent of surface, and both of these factors tend toward a minimum and while diminishing liberate energy. In our process such a stress is applied by the extension of the surface of the liquid system. Furthermore, our process operates in such a manner as to tend to undo the effect of this stress by the production of compounds having a smaller surface tension than the compounds from which they were derived. In most cases in carrying out our process, the production of compounds having low molecular weights is favored. Another stress which is applied in our process is a change in temperature, and in accordance with the law of liquid systems, above referred to, the result in our process is to bring about reactions which are endothermic, as our process involves the application of an increase in temperature. We, however, avoid unduly high temperatures, so as to provide fuel economy, and avoid as much as possible wear and tear on the apparatus. Furthermore, in this way, we obviate undesirable secondary reactions which would occur if higher temperatures were used. Again, in our process the effect of changes in concentration is utilized, inasmuch as the desired reactions are carried out without the disadvantage of interruption, owing to the fact that the reaction products are continually removed from the liquid system. Our process, therefore, provides a means whereby reactions may be brought about in liquid systems without depending upon the utilization of high temperatures, while at the same time the advantages of moderate

temperatures and changes in the concentration of the liquids present are utilized to the best advantage. From a practical standpoint, therefore, our invention is especially useful in that by its use, chemical equilibria are displaced with production of desired reaction products, and in that it greatly increases the velocity of the chemical reactions desired, continually removes the reaction products, and continually provides the necessary heat under controlled conditions.

In general, our process comprises a method which may, if desired, be carried out advantageously by allowing drops of a liquid obtained as a result of the action of surface tension on descending streams or cylinders of said liquid to fall onto and be carried into a second liquid which serves as a splash medium and as a source of heat. The second liquid may or may not be soluble in the first liquid. Furthermore, while the chemical change is taking place in the first liquid, there is a vapor phase containing molecules of said two liquids, as well as of the products formed as a result of the reaction. Preferably, the drops of liquid should be at least one-thirty-second of an inch in diameter in order to produce a proper splash phenomenon. However, when working with a rapid increase of temperature and frequent renewal of the surface, the drops would preferably be larger and at least one-sixteenth of an inch in diameter. If the drops were of a much smaller size, there would be a correspondingly great loss of the liquid by vaporization and mechanical removal before it reaches the splash medium. Furthermore, the extent of the splash phenomenon is dependent on the momentum of the drop, which is influenced by the velocity of the vapor above the splash medium. The extent and nature of the splash phenomenon is further influenced by the surface tensions of the two liquids, by the viscosities of said liquids, and in general, by the nature of the liquids. The effect of an extensive and pronounced splash phenomenon is to very greatly extend the adjacent surfaces of the two liquids in question, and this effect is greatly accentuated if the drop of the first liquid penetrates into the splash medium, there, as a result of the violent heating, to be disrupted into a very large number of small droplets within the same. In case a particular drop does not entirely penetrate the splash medium, it will at least form a distinct impression in the surface of the splash medium, will then rebound upwardly and oscillate back and forth in this way until it finally comes to rest on the surface of the splash medium. In either of these cases, the drop of liquid may, of course, become partly absorbed by the splash medium, partly evaporated, and in part changed chemically owing to the positions of the liquid sur-

faces adjacent to one another, and to the heat transferred from the splash medium thereto. Similar results are also not only obtained while the liquid is in the form of drops, but also in the quantity of the liquid which spreads out upon the surface of the splash medium, and which may acquire there a thin layer covering the entire body of said splash medium. In any case, the result of the process is a very great extension of the surfaces of both liquids and of the surface of contact between them. Inasmuch as the reactions taking place at the surfaces of the liquids are endoenergetic, and also that there is a continual vaporization of liquids, there is consequently a continual absorption of heat. Because of the thin bodies of liquids to which heat is to be transferred from the splash medium, the absorption of heat is very effective. However, such transfer of heat is very much facilitated by providing agitation for the liquids. This may be done mechanically in any desired manner, or by utilizing a splash medium having a temperature that will bring about a continual gentle ebullition thereof. Again it is desirable to renew the heated surface from time to time in order to furnish a splash medium having the proper surface energy and proper molecular orientation, and this may be done by stopping the introduction of the liquid drops for certain intervals of time, or by agitation or ebullition, as above indicated. For example, the drops of liquid may be introduced for periods of three minutes, and the supply of liquid may be discontinued in the intervening periods of one minute. If the process were not carried out in this way, but the drops of liquid were introduced continuously, there would result a substantial equilibrium between the rate of heat introduction into, and the rate of heat abstraction from the surface of the splash medium. This would necessitate a higher temperature for the splash medium in order to maintain the surface thereof at the desired temperature, than is the case when the drops of liquid are supplied intermittently. Due to the utilization of the surface for reaction, there may have been a further surface modification such as change of molecular position in addition to temperature change. By the intermittent supply of the drops of liquid, therefore, the splash medium may be maintained at a lower temperature and proper surface condition.

Owing to the great increase in the demand for motor fuels and the limited supply of petroleum, which is continually becoming less able to furnish the desired quantity of motor fuel, we have applied our process especially to the production of motor fuels from petroleum products which are heavier than the products which are ordinarily contained in motor fuels used in internal com-

bustion engines. For this purpose, we have applied our invention particularly to the treatment of residuums, tars, fuel oils, and similar hydrocarbons, although our process 5 is applicable also to the treatment of gas oils, burning oils, and similar distillates. Previously, no process has successfully handled the heavy oils, such as the residuums, tars, fuel oils, and the like.

10 In former processes, there were obtained a number of undesirable results, such as the formation of olefins, aromatic compounds, high boiling compounds, carbon, and gas. Olefins have the disadvantage of being 15 easily oxidized, and thus forming compounds which will gum up the mechanical devices in which the fuel made therefrom is utilized. Furthermore, both the olefin and aromatic hydrocarbons produce large quantities of carbon in internal combustion engines. In such previous processes ordinarily, furthermore, in which the yield obtained in a single processing amounted to 20 15% of low boiling products which may be called gasoline, the low boiling products so obtained contained at least 20% and in the majority of cases 30% of olefins. Also, such gasoline would have a gravity approximately 25 5° Bé. lower than a distillate of similar boiling range obtained by the distillation of crude oil. In accordance with our process, we obtain 20% of gasoline and less than 15% of olefins. Furthermore, the gravity thereof is substantially the same as a 30 distillate of the same boiling range obtained from crude oil. Besides, these results are obtained by utilizing temperatures between 650° and 750° F., although the temperature may, if desired, be considerably below or 35 above these figures. Also, with our process no pressure is necessary. In our process, in contrast with previous processes, products such as residuums, tars, fuel oils, and all similar heavy oils are successfully treated, 40 and are preferred raw materials, although, if desired, lighter distillates, such as gas oils or kerosene, may be treated together with said residuums, tars, fuel oils, and heavy oils.

45 50 Further objects of our invention will appear from the detailed description thereof contained hereinafter.

While our invention is capable of embodiment in many different forms, for the purpose of illustration we shall describe certain forms of the same hereinafter, and while it is capable of being carried out in connection with many different types of apparatus, we have shown only one type of apparatus in the accompanying drawings, in which:

Fig. 1 is a diagrammatic vertical section of an apparatus which may be used in accordance with our invention.

55 Figs. 2^a to 2^f are a series of diagrammatic

views of the action of the drops upon the surface of the liquid in the still, and

Figs. 3^a to 3^f are similar series of views showing the action of the drops when entering a body of the liquid.

For example, in carrying out our invention, a heavy oil, such for instance as a residuum having a specific gravity of from 14 to 16° Bé, is introduced into a horizontal cylindrical still 1 heated by means of a fire box 2 provided with an air or steam blast oil burner 3, and having a stack 4 to carry off the products of combustion. In the fire box 2, there is located an elevation 4^a to bring the heated gases nearer the still at the rear thereof. Said heavy oil is introduced into the still through a pipe 5. At the top of the still there are two ventilating manholes 5^a and 5^b and a steam pipe 5^c for purging. At the bottom of the still, there is a manhole 6 for cleaning out the carbon and carbonaceous residues from the still, and at the bottom there is also provided a draw-off pipe 7, the discharge from which is controlled by a hand valve 7^a to conduct away the heavy tar to a water-cooled cooler 8 adapted to discharge into a tank 9 having a valved draw-off pipe 10 and a valved inlet pipe 11 for the introduction of any lighter products, when desired. The temperature in the still 1 is gradually raised until the boiling point of the heavy oil is reached which may be from 600 to 700° F. The vapor coming from the heavy oil is carried through a pipe 12 having lagging 13 to a water-cooled dephlegmator 14 having a hand hole 14^a, and provided with lagging 15, and which may be heated by means of a steam coil 16. The dephlegmator 14 is cooled by water passing through horizontal pipes 16^a supplied by a pipe 16^b and allowed to flow out through one or more of a series of valved draw-off pipes 16^c. The condensed liquid which accumulates in the dephlegmator may be caught in a tank 17 by means of a valved inlet by-pass pipe 18, said tank having another valved inlet pipe 18^a, a steam heating coil 19, and a valved outlet pipe 20, which may be also enclosed in the lagging 21 that surrounds the tank 17. The oil is then allowed to run from the tank 17 back into the still, preferably through a plurality of alternately operable filters 22 and 22^a, a meter 23, a stop cock 23^a, as well as a check valve 24 and a preheating coil 24^a, the liquid being discharged into the still from a series of horizontal pipes 25 having overflow outlets 25^a, and supported by turnbuckle straps 25^b, said pipes 25 having perforations 26 adapted to form cylinders 27 of discharged oil which will break into drops 28. These drops 28 upon striking the surface of the liquid in the still 1, in case they do not entirely enter and become separated from the surface of the liquid in the still 1, will partly

enter the same and oscillate back and forth, as indicated in the series of diagrams contained in Fig. 2. If, however, they do enter the body of said liquid and become separated from the surface of the same, the action of the drops within the body of liquid in the still is then indicated in the series of diagrams appearing in Fig. 3. The pipes 25 will thus provide a uniform distribution of the drops over the surface of the liquid in the still 1. If desired, furthermore, the pipe 20 may contain an intermittent supplying device 29 to supply the liquid for example at every alternate three minutes. This 15 may be comprised of a rotating valve 29^a having a gear 29^b, and driven by a gear 29^c on an electric motor 29^d.

Reactions of the type above referred to, will then take place between the surfaces 20 of the drops and the body of liquid in the still, as well as any accumulation of the liquid from the drops on the surface of the liquid in the still, and the ebullition of the liquid in the still will provide the desired 25 agitation hereinabove referred to. It is desirable to have the oil which returns to the still maintain its temperature as far as possible when leaving the still, in order to make possible more accurate temperature control 30 and to avoid using up unnecessarily the heat in the surface of the body of oil in the still, and for this purpose, the pipe 13, the dephlegmator 14, the tank 17, and the return pipe 20 are provided with laggings. The 35 resulting vapor issuing from the still will now be composed of low boiling and higher boiling hydrocarbons, and the dephlegmator will remove the higher boiling hydrocarbons while allowing the low boiling hydrocarbons 40 to pass out by a valved pipe 30 to a water-cooled condenser 31 having water inlet and outlet pipes 31^a and 31^b, and a discharge pipe 32 provided with a sight box 32^a leading to a tank 33 having a valved outlet pipe 45 34. Connected to the lower portion of the condenser 31 and the outlet pipe 32, there is a gas take-off 34^a. If it is desired during the operation of the process, any other distillate, such for example as gas oil or kerosene, may be introduced into the tank 17 50 through the pipe 18^a.

The process as described is continued for any number of hours desired, but ordinarily for a period of about sixteen hours, the 55 temperature of the heavy oil in the still being gradually raised in order to keep up the gentle ebullition therein. At the end of this period, a heavy tar will be left in the still which is run through the cooler 8 into the 60 tank 9, where it may be thinned by adding any desired quantity of a heavy petroleum distillate through the pipe 11 to make a fuel oil, or other heavy product. After making a few runs in this manner, it will be found 65 that a certain amount of carbon or very

heavy tarry material is left on the inner walls of the still, and consequently it will then be necessary to discontinue the operation of the same, allow it to cool, and then be thoroughly cleaned through the manhole 70 6 with the aid of the ventilating manholes 5^a and 5^b.

It will be found that as a result of the process on the basis of the original oil as 100%, the quantities of the several products 75 obtained are approximately as follows:

	Per cent.
Gasoline	20
Kerosene	15
Gas oil	20
Fuel oil or residuum	40
Loss—cracking and refining	5

However, under very favorable conditions the gasoline obtained may be as high as 85 30%.

If desired, as a modification of our invention, gas oil may be used in the still 1, but inasmuch as the liquid would boil away at temperatures below the working temperatures of the process in the ordinary operation of the same, the valve in the pipe 30 would be partly closed in order to have a back pressure on the still, and under these conditions the boiling point of the liquid 95 would be raised sufficiently to prevent it boiling away below the desired temperature. In the event of operating the process in this way, the parts of the apparatus would be made sufficiently strong to withstand pressures up to several atmospheres, for example 100 150 pounds per square inch. By the use of this modification of our process, gas oils can be cracked more quickly than in the case of previous processes, and with increased 105 yields.

Another modification of our invention would be in reducing the viscosities of very heavy oils, such for example as those oils which are so viscous that they cannot be 110 transported satisfactorily, either by pipe line or tank car. In accordance with our process, the viscosity of these oils could be reduced to such a point as to enable them to be readily handled, while at the same time producing 115 enough gasoline to pay for the conduct of the process.

While we have described our invention above in detail, we wish it to be understood that many changes may be made there-in without departing from the spirit of our invention.

We claim:

1. The process of converting liquid hydrocarbons into products of lower boiling point 125 which comprises bringing together surfaces of liquid bodies of hydrocarbons at a converting temperature at least as high as the boiling point of one of them, one of said bodies of liquid being uniformly distributed 130

- over the surface of the other and being intermittently supplied thereto, the temperature of the other body of liquid being higher than that of such distributed body of liquid.
5. 2. The process of converting liquid hydrocarbons into products of lower boiling point which comprises bringing together surfaces of liquid bodies of hydrocarbons at a converting temperature at least as high as the boiling point of one of them, one of said bodies of liquid being uniformly distributed over the surface of the other in the form of drops and being intermittently supplied thereto, the temperature of the other body of liquid being higher than that of such distributed body of liquid.
3. The process of converting liquid hydrocarbons into products of lower boiling point which comprises bringing together surfaces of liquid bodies of hydrocarbons at a converting temperature at least as high as the boiling point of one of them, one of said bodies of liquid being uniformly distributed over the surface of the other in the form of drops having a diameter of at least one-thirty-second of an inch and being intermittently supplied thereto, the temperature of the other body of liquid being higher than that of such distributed body of liquid.
20. 4. The process of converting liquid hydrocarbons into products of lower boiling point which comprises heating a body of liquid hydrocarbons to conversion temperature to distil vapors therefrom, condensing relatively high boiling compounds from said vapors, filtering the condensate and returning the same to said body of liquid hydrocarbons undergoing distillation, said condensate being intermittently supplied to said body.
25. 5. The process of converting liquid hydrocarbons into products of lower boiling point which comprises heating a body of liquid hydrocarbons to conversion temperature to distil vapors therefrom, condensing relatively high boiling compounds from said vapors, filtering the condensate and returning the same to said body of liquid hydrocarbons undergoing distillation, said condensate being intermittently supplied to said body.
30. 6. The process of converting liquid hydrocarbons into products of lower boiling point which comprises heating a body of liquid hydrocarbons to conversion temperature to distil vapors therefrom, condensing a relatively high boiling portion of said vapors, and refluxing the condensate to said body of oil undergoing distillation in such manner as to effect distributed contact thereof with the surface of said body, said condensate being intermittently supplied to said body.
35. 7. The process of converting mineral oil into products of lower boiling point which comprises heating a body of mineral oil to conversion temperature to distil vapors therefrom, condensing a relatively high boiling portion of said vapors, and refluxing the condensate to said body of oil undergoing distillation in such manner as to effect distributed contact thereof with the surface of said body, said condensate being intermittently supplied to said body.
40. 8. The process of converting mineral oil into products of lower boiling point which comprises heating a body of mineral oil to conversion temperature to distil vapors therefrom, condensing a relatively high boiling portion of said vapors, and refluxing the condensate to said body of oil undergoing distillation in the form of drops showered upon the surface of said body, said condensate being intermittently supplied to said body.
